BOX FABRICATING MANDREL

Walter C. George, St. Louis, Mo.

Application November 7, 1955, Serial No. 545,361

5 Claims. (Cl. 93—59)

The invention appertains to a mandrel to facilitate the fabrication and erection of boxes and containers made of solid fibreboard, corrugated fibreboard or other similar materials.

Various methods are employed to erect fibreboard boxes and containers. One of the most common methods is to manually erect the container blanks and manually maintain the container parts in position as they are stitched, glued or otherwise secured in place. With the more complex boxes and containers, it is more difficult to manually position and maintain container parts for fabrication. A particular type of container which is in general use for the shipment of bottled beverages and the like, embodies split, half cover members having longitudinal, inwardly disposed flanges or projections located on the inner edges of half cover members. In some embodiments of the multiple trip beverage containers, end cover flanges are also provided. An example of the class of containers referred to is illustrated in the disclosure of Patent No. 2,603,406, issued on July 15, 1952, to Walter C. George. In the various embodiments of the class of containers referred to, various configurations of inwardly disposed cover projections are provided.

It is readily apparent that it is not without some difficulty that the inwardly disposed cover projections and flanges are maintained in proper position as they are glued or sealed together. It is, therefore, an object of this invention to provide a mandrel device adapted to receive the inwardly projecting cover portions in proper relation as the portions are fixedly secured in position.

Another object of this invention is to provide a mandrel adapted to receive inwardly projecting container parts and maintain the container parts in proper position against the outward forces necessary to secure the container parts in place.

A further object of the invention is to provide a mandrel of the type described which may be easily, manually inserted into a partially erected box blank.

Still another object is to provide a mandrel of the type described having a formed opening therein adapted to receive and maintain inwardly projecting container parts in position as the container parts are secured together to complete the fabrication of the container.

These and other objects and advantages of this invention will be apparent to those skilled in the art upon a full and complete understanding of the construction and operation of this device.

This invention consists in the parts, arrangements and combinations of parts hereinafter described and claimed. The accompanying drawings form a part of this specification and like numerals and symbols therein appearing refer to like parts wherever they occur.

Fig. 1 is a front view of a mandrel embodying this invention being inserted into a partially erected container;

Fig. 2 is a top view of a mandrel embodying this invention shown inserted into a container blank;

2

Fig. 3 is a vertical, sectional view along lines 3—3 of Fig. 2;

Fig. 4 is a vertical, sectional view similar to Fig. 3, illustrating the process of inserting the inwardly projecting cover parts into the mandrel device;

Fig. 5 is a vertical, sectional view showing the container parts inserted into the mandrel member;

Fig. 6 is a horizontal, sectional view taken along lines 6—6 of Fig. 5;

Fig. 7 is a horizontal, sectional view similar to Fig. 6, illustrating side pressure applying means being applied to the container and mandrel;

Fig. 8 is a vertical, sectional view taken along lines 8—8 of Fig. 7;

Fig. 9 is a vertical, sectional view illustrating top pressure means being applied to the container and mandrel therein; and

Fig. 10 is a fragmentary, vertical, sectional view of a modified mandrel embodying this invention.

The embodiment of the invention illustrated is particularly adapted to provide a mandrel device for erecting a multiple trip beer container A, such as shown in the accompanying drawings. The container A, Fig. 3, is provided with side walls 11 having integrally connected half bottom flaps 12. End walls 13 are provided with end bottom flaps 14. In the particular embodiment of the container A illustrated, a reclosable means is employed consisting of half cover flaps 15 provided with longitudinal cover flanges 16, Fig. 2, along their free marginal edges and with side cover flanges 17 along their end margins. Each longitudinal cover flange 16 is provided with a substantially co-extensive, longitudinal cover flap 18 foldably connected thereto. Similarly, each side cover flange 17 is provided with an end extension forming a side cover flap 19. The container A, shown in the enclosed drawings, is provided with vertical notches 20 in the upper margins of the end walls of the container. The purpose of the notches 20 will be explained later in the specification.

40 A mandrel B embodying a preferred form of the invention is composed essentially of two longitudinal halves 21 connected to a resilient bottom plate 22. Each mandrel half 21 is formed of outer side posts 23 and inner side posts 24 rigidly connected along outer bottom members 25 and inner bottom members 26 to the bottom plate 22. The outer side posts 23 and the inner side posts 24 are connected to outer top members 27 and inner top members 28 are connected to top transverse pieces 29. Similar bottom transverse pieces 30 complete the rectangular configuration of sections of the longitudinal mandrel halves 21, as shown in Fig. 3. In the particular embodiment of the mandrel illustrated, a series of five rectangular cross-sections are provided to reinforce the mandrel halves 21, however, it is apparent that the number and configuration of the longitudinal mandrel halves may be varied depending upon the strength required. For example, the outer side posts 23 may be replaced by a continuous stiff outer panel if more strength is desired.

65 55 60 65 70 The longitudinal mandrel halves 21 are preferably each substantially less than one-half of the interior width of the container A to thereby provide a void 31 extending centrally and longitudinally of the container. End pressure plates 32, having relatively narrow resilient pads 33, are fixed to the inner top members 28 adjacent the end margins thereof, as shown in Fig. 2. Center pressure plates 34, having relatively wide, resilient pads 35, are positioned centrally of the inner top members 28. The purpose and function of the plates 32 and 34 will become apparent later in the specification.

A resilient bottom pad 36, Figs. 1 and 3, may be fix-

edly secured to the underface of the bottom plate 22. The bottom pad 36 may be formed of sponge rubber, felt or other suitable resilient material.

In order to lock the mandrel halves in position for sealing the container parts, an internal locking means is provided. The locking means of the embodiment illustrated comprises hingedly disposing a locking plate 37 about a pin member 38 which is, in turn, fixedly secured between adjacent outer side posts 23, as shown in Fig. 3. The locking plate 37 is provided with an upstanding release pin 39 fixedly secured thereto and extending, in the secured position of the locking device, substantially above the level of the longitudinal mandrel halves as shown in Figs. 8 and 10. The locking plate 37 is provided with an upwardly projecting catch or barb portion 40 having a generally vertical edge 41 adapted to engage upon a downwardly disposed locking extension 42 which depends from the inner top member 28 and is fixedly secured between adjacent inner side posts 24. A substantially vertically aligned spring member 43 is connected between a top pin 44, disposed between adjacent top transverse posts 29 and to a locking projection 45 fixed to the upper face of the locking plate 37. In the particular embodiment of the invention described, a pair of locking devices is provided, each positioned adjacent the ends of the mandrel halves.

Operation of the device

In using the device described, the side walls 11 and the end walls 13 of the container A are erected into tubular relation and the end bottom flaps 14 are folded inwardly into horizontal relation. The half bottom flaps 12 are folded inwardly and fixedly secured to the previously positioned end bottom flaps 14. The mandrel is then inserted into the partially erected container body as shown in Fig. 1, and adhesive 46 is applied to the underfaces of the longitudinal cover flanges 16, the longitudinal cover flaps 18 and the side cover flaps 19, as shown in Fig. 2. The side cover flanges 17 are then folded upwardly into substantially right angular relation to adjacent portions of the half cover flaps 15. The side cover flaps 19 are then folded inwardly into right angular relation to their adjacent side cover flanges 17. The longitudinal cover flanges 16 are then folded upwardly and inwardly into substantially right angular relation to the adjacent portions of the half cover flap 15. In this position, the longitudinal cover flaps 18 are folded inwardly through an angle of substantially 180° to thereby sandwich the side cover flap 19 between the longitudinal cover flange 16 and the longitudinal cover flap 18, as shown in Fig. 4. The pre-assembled, depending half cover projections are then inserted into the void 31 intermediate the longitudinal mandrel halves 21, as shown in Figs. 4 and 5. In this position, due to the inherent resiliency of the bottom plate 22, the mandrel halves 21 are in a generally vertical position and the pressure plates 32 and 34 preferably do not exert any force against the projecting portions of the container half cover members inserted therebetween.

The container A and the mandrel B therein are then subjected to substantial, external, transverse forces applied by means of a ram device 47 or other preferred means. The external, transverse pressure causes the side walls 11 of the container A to deflect inwardly, thus forcing the mandrel halves 21 inwardly, as shown in Figs. 7 and 8. As the mandrel halves 21 are forced toward each other, the locking projections 41 will engage the locking extension 42, as shown in Fig. 8, thereby maintaining the mandrel halves 21 and the end pressure plates 32 and the center pressure plates 34 into tight, fixed relation against the inwardly projecting container cover parts. In this manner, the inwardly projecting container cover parts are held tightly together until the adhesive or other securing means has had an opportunity to set. In the particular embodiment of the invention, the internal locking means placed one on each end of the mandrel B

maintains internal pressure against the inwardly projecting mandrel parts independent of external forces. In other words, the container and mandrel may be moved from position between the ram devices 21 as the adhesive is set.

The internal locking device of the mandrel may be released by applying external, vertically downward pressure against the outer faces of the half cover flaps 15, as shown in Fig. 9. The external forces may be applied 10 by means of a roller device 48 placed along the conveyor along which the container and mandrel are transported. The vertically downward, external force acts to deflect the half cover members 15 inwardly to engage the upwardly projecting release pin 39, thereby forcing the locking plate 37 downwardly to disengage the locking extension 42 and the catch portion 40. When, as described 15 in the present embodiment, two locking means are employed, it is preferable to provide two rollers, or other pressure applying devices 48, spaced to simultaneously engage the release pins 39 to facilitate the easy release 20 of the locking means.

When the internal locking devices are disengaged, the mandrel halves 21, mounted on the resilient bottom plate 22, are free to spring outwardly into substantially vertical relation. The completely glued and sealed container cover members may then be opened permitting the mandrel to be removed and re-used in the fabrication of the subject container.

The embodiment of the invention described is susceptible 30 of many and various modifications which fall within the scope and spirit of the invention. For example, the thickness of the resilient pads 33 and 35 may be varied to accommodate modified forms of containers which are erected on the mandrel device. It is important that the 35 thickness of the resilient pads 33 and 35 be such as to permit proper placement of the pressure plates 32 and 34 with respect to adjacent portions of the inwardly projecting container cover parts. As will be observed from an examination of Fig. 5, the end plates 32 are positioned 40 closely adjacent the exposed faces of the longitudinal cover flaps 18 before the transverse force is applied to the container and mandrel. The position of the locking extension 42 with respect to the location of the locking projection 45 is designed so as to permit the pressure plates to tightly compress the inwardly projecting container parts during the setting period of the adhesive. The exact position of the pressure plates 32 and 34 and the amount of inward deflection of the longitudinal container halves required to engage the locking device depends on the number of thicknesses or caliper of inwardly projecting cover material and the characteristics of the material from which the container blank is formed. For example, when highly compressible container material is employed, it is desirable to provide considerable 50 pressure and deflection of the longitudinal mandrel halves 21 inwardly through a substantial distance. It has been found, however, that for solid fibreboard material, such as used for the multiple trip beverage containers, well-known in the trade, an inward deflection of approximately one inch is satisfactory. The fundamental criteria 55 of the function of the internal locking means of the invention is to maintain the mandrel halves inwardly so that the space between adjacent end and center plates 32 and 34 respectively is slightly less than the combined thickness of the inwardly projecting container parts inserted therebetween. The resilient pads 33 and 35 not only thereby provide an even pressure against all portions of the inwardly projecting cover parts, but act to resiliently maintain the pressure plates in position against 60 the container cover parts through material, inherent variations in caliper which are encountered in commercial fibreboard products.

Fig. 10 illustrates a modified form of a mandrel employing this invention wherein a relatively shallow, modifying 65 void 31a is provided along the upper portions of

the longitudinal mandrel halves 21. In the particular embodiment shown in Fig. 10, the margins of the mandrel halves 21, defining the void 31a, are disposed in substantially horizontal alignment, however, various other shapes and configurations of modified voids may be employed to accommodate inwardly projecting container portions of varying cross sectional shapes. Also, the position of the pressure plates and the resilient pads which extend into the modified void 31a may be varied to firmly conform and engage modified inwardly projecting container parts.

It is to be understood that the embodiments herein described are illustrative and not restrictive, and it is also to be understood that the invention may be susceptible of embodiment in other modified forms, and that all such modifications which are similar or equivalent hereto come equally within the scope of the claims next appearing.

What I claim is:

1. A fabricating mandrel for a box having inwardly projecting, adhesively coated, closure flange parts, the mandrel comprising a body portion generally conforming to the interior of the box, the mandrel body portion being formed to provide a void therein to receive the unsealed closure flanges, momentary external force applying means engaging the box into contacting relation against the mandrel to engage the mandrel body portion defining said void into firmly contacting and engaging relation against the inwardly projecting box parts, self acting internal means carried by the mandrel for maintaining continuous force against the said inwardly projecting closure flanges to adhesively fix the inwardly projecting closure flanges in position.

2. A mandrel for boxes with half cover members having longitudinal cover reinforcing flanges extending into the interior of the box, the mandrel comprising a body portion generally conforming to the interior of the box and divided into substantially equal parts longitudinally spaced to define a void to receive the longitudinal cover reinforcing flanges, the mandrel body parts being laterally, resiliently mounted so that a momentary, independent external force applied to the box and therethrough to the mandrel, inwardly deflects and engages the mandrel body parts with their margins defining the void firmly compressing and retaining the cover reinforcing flanges of the box in contacting relation, a transverse locking means being provided to releasably maintain the mandrel body halves in an inwardly deflected position to firmly engage and contact the cover rein-

forcing flanges, said release action accomplished by independent means exterior to the mandrel enclosing box.

3. The invention set forth and claimed in claim 2 wherein the locking means comprises a horizontal latch vertically, resiliently mounted on one mandrel body half with at least one vertically extending locking projection adapted to engage onto the opposite mandrel half to maintain the mandrel halves securely inwardly.

4. The invention as set forth and claimed in claim 3 wherein a vertically disposed releasing means is secured to the locking latch and extends upwardly above the level of the mandrel half to which the latch is secured.

5. A mandrel for boxes with half cover members having longitudinal cover reinforcing flanges extending into the interior of the box, the mandrel comprising a pair of body portions generally conforming to the interior of a box, said body portions being spaced from one another and having opposed spaced pressure applying surfaces thereon defining a void therebetween adapted to receive the reinforcing flanges of a box, means resiliently connecting said body portions for rocking movement toward and away from one another, a locking means supported by one of said body portions and a latch means for engaging said locking means pivotally supported by the other body portion, means normally urging said latching means toward said locking means whereby upon application of an independent external force to a surrounding box, the two body portions are rocked toward one another and the latching means moves into locking relationship with said locking means for maintaining the body portions in such inwardly rocked position, said pressure applying surfaces engaging the flanges of a surrounding box for firmly retaining them in contacting relationship with one another, and a release means connected to said latching means and extending outwardly of said body portions whereby the release means is adapted to be engaged by applying pressure to a surrounding box to release said latch means from locking engagement with said locking means.
